UNITED STATES PATENT OFFICE.

JOHN C. SHEPARD, OF NORWAY, MAINE.

ARCH-SUPPORTER.

977,684.

Specification of Letters Patent. Patented Dec. 6, 1910.

Application filed June 3, 1908. Serial No. 436,416.

To all whom it may concern:

Be it known that I, JOHN C. SHEPARD, a citizen of the United States, residing at Norway, county of Oxford, State of Maine, 5 have invented a certain new and useful Improvement in Arch-Supporters, of which the following is a specification, reference being had therein to the accompanying drawings.

My invention has for its object to provide 10 a cheap and adequate stiffener for the instep of a shoe which may be readily applied to a shoe by the ordinary shoemaker or cobbler, so that it may be sold for a small price and be directly accessible to the wearers of shoes.

15 Heretofore various forms of arch supporters and shank stiffeners have been employed, some of these being intended to be fitted within the shoe, and some between the layers of the shank. These devices require 20 either that the stiffener be especially constructed to fit the foot of the wearer or else that the shoe be originally constructed with a stiffener. As is well known arch supporters which are made to fit the peculiar 25 form of the wearer's foot are very expensive and on the other hand shoes constructed with the stiffener in the shank of the shoe rarely fit the foot well enough so that they 30 may be used without causing the wearer discomfort.

The device embodying my invention is adapted to be applied to any shoe and particularly to those which have assumed the shape of the wearer's instep through use; 35 they may also be satisfactorily applied to new shoes. The device embodying my invention, by reason of its peculiar construction and arrangement, does not add perceptibly to the weight of the shoe, but nevertheless affords a complete support for the 40 instep of the wearer throughout its entire area.

I am aware that stiffeners have been applied to the exterior of a shoe, but so far as 45 is known to me, when so applied, they have not afforded a support for more than a small portion of the instep, thereby resulting in failure to perform the office required of them and in discomfort and inconvenience to the 50 user.

My invention has the added advantage 55 that it may be readily applied to the shoes by any cobbler and when applied to shoes which have previously been worn serves to retain them in the shape which they have received from contact with the wearer's foot.

The construction of my improved arch supporter is such that the weight is distributed over the entire shank of the shoe, thereby making it possible to afford more 60 complete support, while at the same time the arch supporter is more durable and less likely to get out of shape with use.

The invention will be fully understood 65 from the following description taken in connection with the accompanying drawings, and the novel features thereof are pointed out and clearly defined in the claim at the close of the specification.

In the drawings,—Figure 1 is a perspective view of a shoe provided with an arch supporter embodying my invention. Fig. 2 70 is a bottom view thereof. Fig. 3 is a section on line 3—3 Fig. 2.

Referring to the drawings,—My improved 75 arch supporter consists of two side portions B and A which follow substantially the curve of the inside line of the shank of a shoe and the outside line thereof respectively, and of a transverse portion C which 80 lies across the portion of the shoe just back of the ball of the foot in such a position that it will not ordinarily contact with the ground being slightly above the level of the ground by reason of the curve of the shoe. 85 The rear ends of the side portions of the arch, supporter extend rearwardly under the heel F as shown at D and E for a short distance so that the curve of the shank and the relation between the heel and the shank 90 shall always be maintained in the condition intended. I find this arrangement important as otherwise the shoe tends to bend at the line of union between the heel and the shank. The arch supporter is attached 95 to the shoe by nails H or the like, and the said nails extend through the outsole, upper, and insole and at the rear through the counter, if the counter extends far enough forward. The nails are securely 100 clenched on the inside. By this arrangement, all the parts are secured together much more firmly than has hitherto been possible and all possibility of working is entirely prevented.

105 The longitudinal portions of the arch supporter are constructed so that in cross-section they are of the shape shown in Fig. 3; that is, the outer edge thereof is bent over the edge of the shank as shown at K. The 110 rib or edge K keeps the arch supporter from bending and greatly increases the strength

and stiffness of the arch supporter without increasing its weight.

I claim as my invention:

In combination with a boot or shoe, a
5 three sided arch supporter comprising two
side strip portions, a transverse strip por-
tion connecting the two forward ends of said
strip portions, said arch supporter being se-
cured to the outer face of the outer sole, the
10 transverse portion lying across the outer
sole of the shoe just back of the ball of the
foot, the two side portions extending rear-
wardly on the outer face of the shank fol-

lowing the contour of the two side lines of
the shank, the open rear ends thereof ex-
tending backward between the heel and the
outer sole near the outer edges thereof and
concealed between the heel and the heel por-
tion of the sole between which it is secured. 15

In testimony whereof I affix my signature, 20
in presence of two witnesses.

JOHN C. SHEPARD.
